(57) **CLAIM**

The ornamental design for a patterned board as shown and described.

DESCRIPTION

FIG. 1 is a top perspective view of a patterned board, showing my design.

FIG. 2 is a bottom perspective view thereof.

FIG. 3 is a top plan view thereof.

FIG. 4 is a bottom plan view thereof.

FIG. 5 is an enlarged view of an area labeled 5 in FIG. 1; and,

FIG. 6 is an enlarged view of an area labeled 6 in FIG. 2. The broken lines in the drawings depict environmental structure and boundaries and form no part of the claimed design.

1 Claim, 6 Drawing SheetsFIG. 1

FIG. 3

FIG. 4

FIG. 5

FIG. 6
